US00D830337S

(12) **United States Design Patent** (10) **Patent No.:** **US D830,337 S**
Yan (45) **Date of Patent:** **** Oct. 9, 2018**

(54) **WIRELESS HEADSET**

(71) Applicant: **SHENZHEN FUSHIKE ELECTRONIC CO., LTD**, Shenzhen, Guangdong (CN)

(72) Inventor: **Xiaohuang Yan**, Fuzhou (CN)

(73) Assignee: **SHENZHEN FUSHIKE ELECTRONIC CO., LTD**, Shenzhen, Guangdong (CN)

(**) Term: **15 Years**

(21) Appl. No.: **29/605,462**

(22) Filed: **May 26, 2017**

(51) LOC (11) Cl. **14-01**

(52) U.S. Cl.

USPC **D14/206**

(58) **Field of Classification Search**

USPC D14/206, 223, 205, 225, 226; 181/129, 181/130, 135; 379/430, 431, 433.13; 381/380, 381, 370, 374, 322, 312; 455/90.3, 575.1, 569.1; D24/174

CPC H04R 25/00; H04R 1/10; H04R 1/105; H04R 1/1066; H04R 1/1016; H04R 5/033; H04R 5/0335

See application file for complete search history.

(57) **CLAIM**

The ornamental design for a “wireless headset”, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view viewed from another visual angle thereof.

1 Claim, 6 Drawing Sheets
